UNITED STATES PATENT OFFICE.

RUSSEL G. WOODWARD, OF WAUKEGAN, ILLINOIS, ASSIGNOR TO UNION SPECIAL MACHINE COMPANY, OF CHICAGO, ILLINOIS, A CORPORATION OF ILLINOIS.

COVER-PLATE FOR SEWING-MACHINES.

1,034,944.

Specification of Letters Patent.

Patented Aug. 6, 1912.

Application filed June 1, 1907. Serial No. 376,780.

To all whom it may concern:

Be it known that I, RUSSEL G. WOODWARD, a citizen of the United States, residing at Waukegan, in the county of Lake, State of Illinois, have invented certain new and useful Improvements in Cover-Plates for Sewing-Machines, of which the following is a description, reference being had to the accompanying drawing and to the letters and figures of reference marked thereon.

In an application filed by me on the 7th day of September, 1905, which application has since been issued as Patent No. 872,601, dated December 3d, 1907, I have shown, described and claimed a cover plate for sewing machines upon which the present invention is an improvement. Said cover plate includes generally a cover plate having means to lock it in its closed position and a single implement independent of the locking means for operating the locking means and moving the cover plate upon its support. Said cover plate has a strip-diverting guide, slideable thereon, normally spring pressed outwardly and adapted when moved to the right by the handle to have an angle piece carried by it, release the locking means. In the use of this device, it has been found that in factories, operators would forget in closing the cover plate, to slide the diverting guide to the right, and in this way it would become bent and cause trouble, either by wrongly diverting the trimmed off strip or by getting in the way of the movable knife. I have, therefore, devised an arrangement, whereby when the cover plate is out of operative position, the diverting guide or sliding plate carrying the same, will be automatically engaged by a trigger and held in retracted position until the cover plate is moved into operative position again.

The invention, therefore, consists primarily of a cover plate having a sliding portion, with means for holding said sliding portion in retracted position when the cover plate is open, and for automatically releasing the sliding portion when the cover plate is closed.

It also consists in the various matters hereinafter described and referred to in the appended claims.

The invention is illustrated in the accompanying drawings, in which,

Figure 1 represents a side view of a sew-

ing machine embodying my invention; Fig. 55 2 is a perspective view taken from the inner side of the cover plate; Fig. 3 is a sectional view; Fig. 4 is an edge view; and Fig. 5 is a detail view of the locking device for the cover plate, and the automatic trigger for holding the diverting guide retracted.

In these drawings, the hinged cover plate is shown at 38, and it is attached to the bed casting of the machine along its bottom edge by screws 39, and held in place at the top by the spring pin 40, inserted in the top of the central bearing lug for the main shaft and registering with the hole 41 in the cover 38. This cover 38 carries on its outer face a guide 42, for diverting the strip severed from the body fabric toward the front of the machine, and away from its operating parts. This diverting guide is normally spring pressed forward, by means of the spring 43 pressing against the bracket 75 44 secured to the inner side of the cover 38 by means of screws 45 passing through slots 46 in said cover.

On the plate which carries the strip-diverting guide is secured an angle plate 50, 80 having a finger piece 51, the upper arm 52 of said plate 50 having a beveled lower face at one end, so that as the plate 50 is slid to one side, the beveled face of the angle plate will bear against the spring pin 40, and force the same down to release the cover, which can then be swung down by means of said finger piece.

Thus far the construction of the cover plate is the same as set forth in my above 90 entitled application. To avoid the practical difficulties referred to as existent in the use of this device in case of oversight or carelessness on the part of operators, I have provided means whereby when the diverting 95 guide or sliding plate is moved to the right, and the locking means for the cover plate released, and the cover plate begins to be swung outwardly, said sliding portion will be engaged and held in retracted position 100 during all the period the cover plate is opened, and automatically release the same when the plate is closed again. The device for accomplishing this object as herein shown, embodies a hinged gravity trigger or 105 catch 53, pivoted to the cover plate as at 54, and having a notched portion 55 to engage the angle piece 52. This trigger or catch

has a pin 56, projecting through an opening in the cover plate, this pin being of such length that when the cover plate is closed the pin strikes against the central lug of the machine, and is raised, thus raising the notched portion 55 from engagement with the angle piece 52, thus allowing the spring 43 to move the diverting guide to the left.

In operation, when it is desired to open 10 the cover plate, the sliding of the finger piece forces down the locking pin 40, and unlocks the cover plate. As soon as the lat- 15 ter is turned on its hinges, the gravity trig- ger engages the angle piece 50, and holds the sliding plate or diverting guide retract- 20 ed during all the time the cover plate is open. In closing the latter, as soon as the pin 56 strikes the top of the central lug, the gravity trigger or catch 53 is swung upward on its pivot, releasing the sliding plate or diverting guide, which under the action of the spring returns to normal position.

Having thus described my invention, what I claim as new and desire to secure by Letters Patent, is:—

1. A cover plate for sewing machines adapted to be opened and closed, comprising sections, one of which is movable relative to the other, means for holding said movable section in retracted position when the cover plate is open, and means for releasing the movable section as the cover plate is closed.

2. A cover plate for sewing machines adapted to be opened and closed, comprising sections, one of which is movable relative to the other, a spring for sliding said movable section on the other section, means for holding the same in retracted position when the cover plate is open, and means for automatically releasing the movable section when the cover plate is closed.

3. In a sewing machine, a sectional cover plate attached to and supported by a sta- 45 tionary part of the machine frame, and adapted to be opened and closed, means for locking the cover plate in its closed position, means for moving a portion of said cover plate laterally, and simultaneously operat- 50 ing the locking device, means for holding the said portion in retracted position when the cover plate is moved, and means for releas-

ing said portion when the cover plate is locked.

4. A cover plate for sewing machines 55 adapted to be opened and closed, comprising sections, one of which is movable relative to the other, a catch engaging and holding said movable section when in retracted position, a member carried by the catch and 60 adapted when the cover plate is closed to move into engagement with a part of the machine frame and release the catch.

5. A cover plate for sewing machines adapted to be opened and closed and having 65 a movable section, a pivoted gravity catch engaging and holding said movable section when in retracted position, and a pin carried by the catch projecting through the cover plate, adapted when the cover plate is 70 closed to move into engagement with a part of the machine and release said catch.

6. A cover plate adapted to be opened and closed, comprising sections, one of which is movable relative to the other, means for 75 holding said movable section in retracted position when the cover plate is open, means for releasing said movable section, whereby the same may be returned to normal opera- 80 tive position when the cover plate is closed including a single lever.

7. A cover plate adapted to be opened and closed, comprising sections, one of which is movable relative to the other, means carried by said cover plate to move said movable 85 section laterally and simultaneously unlock the cover plate, and means for locking said movable section in its laterally adjusted position.

8. A cover plate adapted to be opened and 90 closed comprising sections, one of which is movable relative to the other, means carried by said cover plate for locking the movable section in inoperative position, means for automatically releasing the same when the 95 cover is closed, and means for locking the cover in closed position.

In testimony whereof I affix my signature, in presence of two witnesses.

RUSSEL G. WOODWARD.
